Primary Examiner — Adir Aronovich*Assistant Examiner* — Ramzi Almatrahi(74) *Attorney, Agent, or Firm* — Fish & Richardson P.C.(57) **CLAIM**

The ornamental design for a charging connector for an automobile, as shown and described.

DESCRIPTION

FIG. 1 is a top, front and left side perspective view of a charging connector for an automobile showing my new design;

FIG. 2 is a top, front and right perspective view thereof;

FIG. 3 is a front elevational view thereof;

FIG. 4 is a top plan view thereof;

FIG. 5 is a right side elevational view thereof;

FIG. 6 is an enlarged cross-sectional view taken along line 6-6 in FIG. 3 with the internal structure omitted;

FIG. 7 is an enlarged view of the portion defined by crop lines 7-7 in FIG. 1;

FIG. 8 is an enlarged view of the portion defined by crop lines 8-8 in FIG. 2; and,

FIG. 9 is an enlarged view of the portion defined by crop lines 9-9 in FIG. 3.

The features shown in broken lines in the drawings depict environmental subject matter only and form no part of the claimed design. The dot-dashed lines denote the boundary of the claim, and form no part of the claimed design.
